Primary Examiner — Sheryl Lane*Assistant Examiner* — Calvin E Vansant(74) *Attorney, Agent, or Firm* — Lewis Roca Rothgerber Christie LLP(57) **CLAIM**

The ornamental design for front outward flange of a vehicle wheel, as shown and described.

DESCRIPTION

FIG. 1 is a perspective view of a front outward flange of a vehicle wheel according to my new design;
FIG. 2 is a elevational view thereof;
FIG. 3 is a side elevational view thereof; and,
FIG. 4 is an enlarged view of the generally oval indent feature of my new design.
The broken lines depict portions of the front outward flange of a vehicle wheel that form no part of the claim.
